UNITED STATES PATENT OFFICE.

ALOYSIUS J. CAWLEY, OF PITTSTON, PENNSYLVANIA.

SOUND-RECORDING PROCESS.

1,420,304.

Specification of Letters Patent. Patented June 20, 1922.

Application filed December 13, 1919. Serial No. 344,708.

To all whom it may concern:

Be it known that I, ALOYSIUS J. CAWLEY, a citizen of the United States, and a resident of Pittston, in the State of Pennsylvania, 5 have invented a new and Improved Sound-Recording Process, of which the following is a full, clear and exact description.

The invention relates generally to sound recording; more particularly it involves a 10 process whereby sound is recorded upon a celluloid or similar film mechanically. A sound record groove may be impressed in a moving picture film as it passes through the camera, thus rendering it possible to record 15 motion and sound, including articulate speech, simultaneously on the same medium.

By this process, the film is for all intents and purposes a wax-like substance only during the actual time of recording, 20 and only at the precise place on the film where the sound is to be recorded. Just as soon as the record is impressed in the medium, the latter immediately becomes hard and tough, precluding any possibility of 25 damage to it. A master record can thus be produced directly on the margin of a motion picture film, from which a metallic or other matrix may be made.

The invention possesses several advantages 30 over photographic methods of sound recording. With such methods it is not possible to obtain the exact form of groove desired, on account of its having been produced by chemical or similar means. With the herein 35 described method, any type of groove, whether V-shape or other, may be impressed; moreover the groove may have the exact dimensions desired. It is to be further noted that any type of sound recording, such as 40 lateral or vertical cut, or a combination of both, may be used with this process. As the matrix is made from the master record directly by means of a simple mechanical operation, the process reduces the art of producing 45 combined sound and picture records on the same medium to the fewest possible manipulations.

Although the invention is especially well adapted for use in producing combined picture and sound records on the same film, it 50 is not at all limited to this field, but may be used for ordinary sound recording, as hereinafter described.

Reference is to be had to the accompanying 55 drawing forming a part of the specification, in which like characters of reference

denote corresponding parts in all the views, and in which,

Figure 1 is a view of the heating device in contact with a celluloid film, together with 60 the sound recorder.

Figure 2 is an elevation view of a plurality of such devices, each independently heated.

Figure 3 is an elevation view of a heating 65 device combined with an auxiliary temperature controller.

Figure 4 is a sectional view of three different types of heating device.

Figure 5^a is a sectional view of a heating 70 device in contact with the film on its sprocket wheel.

Figure 5^b is a plan view of the heating strip in contact with the margin of the film.

Figure 5^c is a plan view of a modified 75 form of the heating strip.

Figure 6 is an elevation view of liquid heating device.

Figure 7^a is an elevation view of a device intended to remove the film from contact 80 with heat strip.

Figure 7^b is a side elevation view of the same device.

It is a well known fact that celluloid, when 85 heated to a certain temperature, becomes plastic. If, therefore, a celluloid or similar film is raised to the proper temperature, and a recording stylus placed in contact with it, sound may be recorded as readily upon it as upon wax. The entire film cannot be heated 90 while passing through the camera mechanism, because it would become distorted and rendered unfit for further use. The invention avoids this difficulty by heating a section of the film that is substantially of only 95 a slightly greater width than that occupied by the sinuous sound groove.

Figure 1 shows a simple device which accomplishes this, and which may be attached to any motion picture camera. The film A 100 passes from the magazine 30 to the right and passes around the sprocket wheel 12. The loop adjacent to the film gate 15 is shown at 13. In contact with the film is the metal strip 1, which may be of copper; this is 105 traversed by an electric current for the purpose of elevating its temperature. This strip is supported by the body 3, preferably of wood or other nonconducting material. One extremity of this strip is attached to the lever 16, which is pivoted at 17, and presses 110 against the contact point 5. When the metal

strip 1 becomes heated above the desired temperature, it is readily seen that the contact at 5 will be broken, due to the expansion of the strip. The film A can be close to, 5 or in actual contact with the heating strip 1, as desired. It is obvious that the celluloid adjacent to this strip will be rendered plastic thereby. It will, therefore, form a very sensitive sound recording medium for the 10 stylus 8, which is located close to the end of the heat strip. Just as soon as the record is impressed, the film passes away from the heater and down over the sprocket wheel 12. Cooling, and consequent hardening of the 15 film immediately sets in. However, as the softened portion is enclosed on either side by a hard, tough film of cold celluloid, there is no considerable danger to the sound record. If the recording stylus is placed at 20 a point where the film is moving at uniform speed and in advance of the loop, since this latter is vibrating rapidly, advantage can be taken of its cooling or fanning action. In the appended claims, therefore, the loop is 25 referred to as a vibrator. As the device as a whole resembles a thermostat, adjustment of contacts similar to that shown at 5, renders it possible to keep the heat strip at any desired temperature. There is, therefore, no 30 danger of overheating or igniting the film. The heating circuit is shown diagrammatically, 4 being a source of power, such as a dynamo, dry battery, storage battery, etc. A switch is shown at 6, which may send the 35 current either through the heating circuit, or through the meter 7 in order to ascertain the amount of energy in the circuit, etc. The sound recorder is shown at 9; it is preferably a combined microphone and sound recorder. 40 It is obvious that the heater may be at a temperature considerably in excess of the desired temperature of the film. Since the latter is moving at a fair speed, unless a comparatively great length of heating 45 surface is provided, the film will not attain the same temperature as the heat strip during such comparatively short period of contact. In general, the hotter you make the heat strip, the shorter it may be. However, there 50 is a possibility that in practice, the film may not be heated to its actual plastic temperature, as it may be found that the sound can be recorded satisfactorily at a lower temperature. 55 The heater may be of any desired length; it may also be of a form designed to insure contact with the film as it turns back and forth in the camera. Furthermore, the heating may be accomplished by means of several 60 independently operated electrical heaters. This is illustrated in Figure 2, where the film A passes from the magazine over the sprocket wheel at the right and comes in contact with the U-shaped heater, and down- 65 wards over the sprocket wheel 12, through

loop 13, to the film gate 15. The wheel 14, which may be provided with sprocket teeth and connected by suitable gearing such as shaft 33 and gears 31, 31', 32 and 32', supported by bearings 34 and 34' to the driving 70 mechanism of the camera, assists in moving the film over the curved surface. There are two heating units 65 and 66 connected in parallel as shown, so that lack of uniformity in heating is minimized. The heat controlling members are somewhat different from those shown in Figure 1; a new member 2, such as an ebonite strip, having a coefficient of expansion greater than the metal strip 1, is introduced. This renders the device more 75 sensitive to heat fluctuations. The heat controlling device shown at the right, which is similar to that described in Figure 3, is constructed of two members, 1 and 2, which may be made of metal and ebonite respectively 80 and rigidly attached; the coefficient of expansion of ebonite is much greater than that of the metal. Upon heating the combined strips, they bend away from the contact point and thus shut off the electric current. 85

Figure 3 shows a heating device connected with an auxiliary safety device, which may be a fuse or any kind of thermostat, for instance of the fluid column type. A fuse is illustrated in the figure. In the compartment 10, it is shown at 11. The recorder 9 shown in this figure and also in Figure 2, is provided with a bell crank so that the plane of the diaphragm is parallel to the film surface. 95

In Figure 4 three cross-sectional views are shown, illustrating different arrangements of the heat strips. The central view shows that the heat strip may be much narrower than the body of the heater proper. The third view illustrates the fact that the heat strip may be held close to, but not in actual contact with the film. 100

The recording stylus passes through the heater body by means of a groove, which 110 must be of a width substantially greater than the greatest amplitude of vibration of the stylus. Figure 5^a shows the stylus 8 in its groove, which is formed in the supporting body 3 and heat strip 1. The film margin is shown at A resting upon the sprocket wheel 12. Figure 5^b shows the device with everything removed but the heat strip 1, which rests upon the margin of the film A. The stylus point 8 impresses the record 120 groove 21. Figure 5^c illustrates a modification of the heat strip 1, whereby all possible danger of imparting any heat to the film after the record has been impressed upon it, is avoided. To accomplish this, the strip is 115 bent to one side as shown. 125

If it is desired to take a further precaution against over-heating the film, a fluid heater may be used. Figure 6 shows an oblong metal container 28, preferably of 130

wedge-like cross section, having its narrow-
est surface in contact with the film A. This
container is filled with water, an aqueous sol-
ution, or a fluid having a higher boiling
5 point than either of those, as desired. Elec-
trical heaters 27, such as coils of wire, are
located in this liquid, and maintain it at its
boiling point. The liquid could also be
heated by passing a suitable current directly
10 through it, if it is ionizable. The vapors
pass through the tube 29, which acts to a
certain extent as a reflux air condenser,
bringing most of them to the liquid condi-
tion again. If desired, the tube may be ar-
15 ranged in the form of an air cooled coil 35,
which will still further reduce the loss by
evaporation. The stylus 8 is shown at the
left of the heater.

Figure 7^a is a transverse view and Figure
20 7^b is a side view of a device designed for
the purpose of lifting the film away from
the heater. This is desirable, for instance
when the film is stopped and it is not de-
sirable to turn off the electric current. Any
25 possible damage caused by leaving the film
in contact with the heat strip for an exces-
sive period is thus avoided, particularly if
the heat strip is at a temperature greater
30 than the plastic temperature of the cellu-
loid. It consists of a metal frame 23, pass-
ing through guides 24 and supporting the
rolls 22. A number of springs, one of which
35 is shown at 18, supported by the shelf-like
extension of the frame, hold the film nor-
mally in contact with the heat strip. Any
kind of cushions, pneumatic 37, fibrous 38
or other, may be substituted for the springs.
The frame is moved downward by means of
40 the crank arm 26, which is connected by
means of a shaft 39 to an operating lever
40 or similar device located on the outside of
the camera.

In the actual operation of the apparatus,
it is only necessary to turn on the heater
45 by closing the electrical circuit by means of
switch 6, while focusing, and when the de-
sired temperature is reached, the film is
moved, when the sound record will be im-
pressed in the softened celluloid.

50 An absolutely uniform speed is necessary
for sound recording, and for this reason the
camera should be driven by some form of
motor. A small generator 47 may be oper-
ated by the motor in order to furnish the
55 heating current. However, inexpensive,
small dry batteries may be used for this pur-
pose.

As the heat strip is surrounded by heat
60 insulators 3, there is a considerable saving
of current. It is not necessarily made of
metal, as some other material such as ebo-
nite may be used. Moreover, as the heated
section or that part of the film in which
the record 8 is impressed, is located between

the edge of the film and the row of sprocket
holes, no damage can be done to the film,
there being no strain tending to stretch or
shear it along this section. Instead, the
70 sprocket wheels, such as 12 etc., rather tend
to hold it together as it passes around them.
Further, it is desirable to have the heated
section slightly nearer to the edge of the
film than to the row of sprocket holes.

If a liquid heating device is used, it
75 should be provided with a transparent sec-
tion 41, in order to ascertain the amount of
liquid present. Any liquid of constant boil-
ing point may be used, a fixed temperature
being thus assured.

The meter 4 shown in the electric heating
80 circuit is preferably a small combined am-
meter and voltmeter as is ordinarily used
with dry batteries.

The exact location of the recording of the
sound is not limited to any particular place
85 on the film; it may be recorded before or
after the point of exposure of the picture,
but should be at a point where the film is
running with a uniform speed.

The result of the process is a negative mo-
90 tion picture film having its appropriate
master record located in the film body, pref-
erably on a margin or margins. A matrix
can be made from this.

Where rolls are mentioned in the specifi-
95 cation, it is to be definitely understood that
any means of impressing heat and pressure
is designated.

The invention is not limited to the re-
cording of sound, or the contacting of the
100 stylus on the celluloid side of the film, as it
may be recorded on the gelatine side, if de-
sired. The gelatine, being flexible, may be
displaced downwards into the celluloid body.

The term heater embraces the compactly
105 arranged heater as a whole composed of the
elements 1, 3 etc., including the temperature
regulator, such as 5, 16. By heat strip is
implied the strip or strips 1, 2, concerned
with the direct heating of the film. It is to
110 be definitely understood that the invention is
not limited to any particular type of tem-
perature regulator. That shown being rather
a general representation than a specific type.
By adjusting the contact points 5, a definite
115 temperature may be secured with great
nicety. It will thus be found that by ad-
justing the contacts, a certain degree of soft-
ness of the film A will be secured at which
the most satisfactory sound recording may
120 be accomplished. This, however, may not
be the temperature at which the medium
finds its greatest plasticity. The invention
is therefore, not limited to the attainment, or
maintenance of any particular temperature.

125 One can readily see that the three main
elements of the combination, heater, recorder
and recording medium, constituting the re-

cording device, may be placed in numerous arrangements without departing from the spirit of the invention.

All of the drawings are made on an enlarged scale. It is obvious that the actual dimensions of the devices may be of any desired magnitude to best meet actual conditions in practice.

Having thus described my invention, I claim as new and desire to secure by Letters Patent:—

1. A process of sound recording, which consists in softening a portion of a film made principally of a cellulose derivative by means of heat which is below the ignition or fusion point of said film, vibrating a stylus in contact with said portion, independently feeding sections of the film to form an intermediate, oscillating loop and accelerating the hardening of said portion by the rapid movement of the loop.

2. A process of sound recording, which consists in applying a non-igniting, non-fusing, plasticizing degree of heat to a portion of the width of a film, preferably on its margin, to soften same, and vibrating a stylus in contact with said softened portion.

3. A process of sound recording, which consists in independently feeding sections of film to form a transversely moving loop, softening by application of heat a portion of the width of a film immediately before said film enters the loop, vibrating a stylus in contact with said portion, and then passing

same through the loop to harden said film.

4. A process of sound recording which consists in applying heat to a portion of the width of a film on and in the immediate vicinity of the proposed sound groove, and impressing said groove by vibrating a stylus in contact with said portion.

5. A process of sound recording, which consists in placing a heat strip in contact with a film to render it plastic along the line of contact, and subsequently vibrating a stylus along the plastic portion.

6. A sound recording device, consisting of a long, narrow heater adjacent to a portion

of the width of a film, preferably on its margin, and a recording stylus acting to impress a groove in said portion.

7. A sound recording device, consisting of an electrical heater and means to prevent attainment of fusion and ignition, which heater closely approaches a moving film or surface, and a recording stylus which impresses a groove in said film.

8. A sound recording device, consisting of a heater provided with auxiliary means for maintaining constant temperature adjacent to a portion of the width of a recording element to soften same, a sound recording stylus vibrating in contact with said portion, and a vibrator to accelerate hardening by rapid vibration of said recording element in the air.

9. A sound recording device, consisting of a film, a heater which softens a portion of the width of said film, a sound recorder whose vibrating stylus is in contact with said portion passing beneath said heater; said stylus impressing a groove in said film, and a film vibrator to accelerate hardening by rapid vibration of said film in the air.

10. A sound recording device, consisting of a heater provided with heat insulators adjacent to a portion of the width of a moving film, a temperature controller, a vibrating stylus so placed as to contact with said portion before it cools, and a film vibrator to accelerate hardening by rapid vibration of said film in the air.

11. A sound recording device, consisting of a heater provided with heat insulators adjacent to a portion of the width of a film to soften same, a vibrating stylus in contact with said softened portion, and a film vibrator to accelerate hardening by rapid vibration of said film in the air.

12. A sound recording device, consisting of a heater provided with heat insulators and a temperature controller acting to soften a portion of the width of a film, and a stylus vibrating in contact with said portion to impress a sound groove therein.

ALOYSIUS J. CAWLEY.
